US00D568307S

(12) United States Design Patent (10) Patent No.: US D568,307 S
Kaneshiro (45) Date of Patent: * May 6, 2008

(54) PORTABLE COMPUTER

(75) Inventor: Tetsuya Kaneshiro, Kadoma (JP)

(73) Assignee: Matsushita Electric Industrial Co., Ltd., Osaka (JP)

() Term: 14 Years

(21) Appl. No.: 29/267,556

(22) Filed: Oct. 17, 2006

(30) Foreign Application Priority Data

Apr. 20, 2006 (JP) 2006-010267

(51) LOC (8) Cl. 14-02

(52) U.S. Cl. D14/315

(57) CLAIM

I claim the ornamental design for a portable computer, as shown and described.

DESCRIPTION

FIG. 1 is a top perspective view of a portable computer of the present invention;

FIG. 2 is a front view thereof;

FIG. 3 is a top view thereof;

FIG. 4 is a bottom view thereof;

FIG. 5 is a right side view thereof, the left side view being a mirror image thereof; and,

FIG. 6 is a rear view thereof.

The ornamental design which is claimed is shown in solid lines in the drawings. Any broken lines in the drawings are for illustrative purposes only and form no part of the claimed design.
